UNITED STATES PATENT OFFICE.

VINCENT J. O'BRIEN, OF DENVER, COLORADO, ASSIGNOR OF ONE-HALF TO A. U. MAGNAN, OF DENVER, COLORADO.

DUST-SCREEN VALVE.

1,176,238.

Specification of Letters Patent. Patented Mar. 21, 1916.

Application filed June 24, 1912, Serial No. 705,517. Renewed July 29, 1915. Serial No. 42,639.

To all whom it may concern:

Be it known that I, VINCENT J. O'BRIEN, a citizen of the United States, residing in the city and county of Denver and State of Colorado, have invented certain new and useful Improvements in Dust-Screen Valves; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in dust screen valves, or valves for use in connection with the introduction of air or other motive fluid to pneumatic tools or other machines operated by air. It is important, 20 particularly in this class of machine, that the air be cleansed or screened of all foreign matter, and especially of particles which are sufficiently large to obstruct the ducts, orifices or ports with which tools of 25 this class are provided.

The special object of my present invention is to provide means for cleansing the screen which has been used to strain out the dust or foreign particles of matter from the 30 air or other motive fluid employed in work of this kind. Heretofore, so far as I am aware, while screens have been employed at some point in the pipe line, or conduit, which carries the motive fluid to the tool, 35 no means for readily cleansing this screen have been devised.

The screen is usually located in a part of the pipe line containing removable parts, and after it becomes obstructed, in order to 40 clean it, the parts of the pipe line where the screen is located must be taken apart, and in many instances it becomes necessary, where working in mines, to send the screen out of the mine for cleaning, thus making 45 the operation very difficult, and, to a very large extent, interfering with the work.

The object of my improvement is to readily cleanse the screen of the collected dust, or debris, without removing it from 50 the pipe line, and to this end I construct a valve and apply the screen to the valve piece, which is rotatable, for the purpose of cutting the air off, or turning it on, in the pipe line, as may be required, this valve

being independent of the throttle valve employed in connection with the tool and directly mounted thereon, hence my improved valve device may be located in any desired part of the pipe line leading to the tool and carrying motive fluid for operating the latter. I prefer, however, to locate this valve close to the tool so that the person in charge thereof may have it readily accessible for manipulating purposes.

It will be understood by those familiar with the operation of tools of this character that the motive fluid for various reasons carries more or less dirt of various kinds, and where screens are employed they gradually become obstructed to such an extent 70 that the passage of the necessary quantity of motive fluid to the tool is prevented. In this event it is essential to the proper operation of the tool that the screen be cleansed. In my improved construction, in order to 75 accomplish this, it is only necessary to impart a partial rotary movement to the rotatable valve piece, in which event small ducts, with which the valve piece is provided, are placed in communication with the air of the pipe line at one extremity, while their opposite extremities lead to the passage through the valve piece in the rear of the screen. When the valve is in this 80 position, there is an opening in the valve casing in front of the screen for the escape of the matter which clogs the screen. In other words, the motive fluid under pressure is introduced into the opening of the valve piece in the rear of the screen and acts 85 upon the latter in the reverse direction from the passage of the air which has been screened by the screen, hence this air, moving through the screen in the reverse direction, readily removes the dirt or debris from 90 the screen and carries it through the aforesaid opening to the atmosphere. This is accomplished very quickly, and, therefore, with only slight interruption of the machine, after which the valve piece may be 95 returned to its normal position, when the passage of the air through the screen continues the same as if it had never been obstructed. I also make provision in the event of the closure of the small ducts heretofore 100 mentioned, for cleansing these ducts by passing air through the said ducts in the reverse from the normal direction of its

passage, the said ducts during this cleaning operation being in communication with small passages in the valve casing leading to the atmosphere.

- 5 Having briefly outlined my improved construction I will proceed to describe the same in detail, reference being made to the accompanying drawing in which is illustrated an embodiment thereof.
- 10 In this drawing: Figure 1 is a side elevation of a pneumatic tool equipped with my improvement. Fig. 2 is a section taken on the line 2—2, Fig. 1, shown on a larger scale. Fig. 3 is a similar view showing the screen valve piece in a different position. Fig. 4 is a similar view showing the screen-carrying valve piece in still another position, being that which the valve piece occupies during the operation of automatically 20 cleaning the screen by the passage of air therethrough in a direction the reverse of its normal passage when on its way to the tool. Fig. 5 shows the valve piece in still another position, being that which it occupies when 25 cleaning out the ducts with which the valve piece is equipped. Fig. 6 is a similar section showing the valve piece in position to cut off the air, or motive fluid, from the tool. Fig. 7 is an exterior view of the screen valve 30 showing the means provided for indicating to the operator when to stop the movement in order to leave the valve piece in the respective positions illustrated in Figs. 2 to 6 inclusive.
- 35 The same reference characters indicate the same parts in all the views.
- Let the numeral 5 designate a pneumatic tool provided with an inlet pipe, 6, for motive fluid, with which is connected a conduit, 40 7, a valve, 8, being located in the conduit, preferably close to the tool whereby the person in charge of the operation of the latter may easily have access thereto for manipulating purposes. This valve, 8, is composed of 45 a casing, 9, and a rotary valve piece, 10, located within the chamber of the casing. As illustrated in the drawing, the opposite extremities of the valve casing are reduced, as shown at 12 and 13. The extremity, 12, 50 is interiorly threaded, as shown at 14, while the extremity 13 is exteriorly threaded, these threaded extremities being arranged to form suitable connections with the conduit members on opposite sides of the valve. As 55 shown in the drawing, the opening, 16, which is internally threaded, constitutes the inlet opening, or the opening through which the motive fluid enters the valve casing on its way to the tool, while the opening, 17, 60 is the opening through which the motive fluid passes after leaving the valve casing.

The valve piece, 10, is operated by means of a handle, 18, which is exposed for the purpose. This valve piece is provided with 65 an opening, 19, which, when the motive fluid

is passing regularly to the tool, is in register with the two openings, 16 and 17, of the valve casing. Stretched across the inlet end of the valve piece opening, 19, is a screen, or mesh diaphragm, 20, which is secured to the valve piece in any suitable manner. As shown in the drawing, the valve piece is provided with shoulders, 21, to facilitate the fastening of the screen thereto in a substantial manner.

At one side of the screen, 20, and formed within the solid part of the valve piece, is a number of ducts, or small passages, 22, which, when the valve piece is in position, as shown in Fig. 2, or when the motive fluid is passing regularly to the tool, are closed at their outer extremities by the valve casing, and consequently perform no function.

However, if it be assumed that the screen, 20, has become clogged with the debris which 85 it has strained out of the motive fluid, whereby it becomes necessary to clean out the screen, the operator will turn the valve piece 10, to the position shown in Fig. 3, or toward the right, far enough to bring the forward extremity 23 of the opening 19

through the valve piece into communication with a port, 24, leading to the atmosphere. The ducts, or passages, 22, will then be in communication at one extremity with the inlet opening, 16, of the valve casing, and at their opposite extremities with the opening 19 of the valve piece in the rear of the screen 20. Furthermore, the forward extremity, 23, of the valve piece opening 19

will be in communication with the inlet opening 16 of the valve casing, whereby the motive fluid will have free access to the forward extremity 23 of the opening 19 for the purpose of removing, through the port 105

24 any dirt that may have accumulated in the forward extremity of opening 19, and which is not directly attached, and clinging to the screen. Then by a further movement of the valve piece into the position shown in 110

Fig. 4, the forward extremity 23 of the opening 19 will be cut off from communication with the inlet opening 16 of the valve casing, but the ducts 22 will still be in communication at one extremity with the inlet opening 16 of the valve casing, and at their opposite extremities with opening 19 in the rear of the screen. The forward extremity, 23, of this opening, 19, is still in communication with the dirt exhaust port 24 of the casing, 120

hence as there is no other outlet for the motive fluid except by way of the ducts 22, the opening, 19, in the rear of the screen, the forward part, 23, of the opening, 19, and the port 24, the ducts 22 will carry the motive

fluid under full pressure and to their full capacity through the screen 20 in a direction the reverse of the passage of the motive fluid, when the dirt accumulated on the screen and this reverse passage of the motive

125 fluid

fluid through the screen, will quickly remove all of the debris therefrom, thus cleaning the screen without removing it from the valve, or disconnecting any parts of the mechanism. Should it then be desired to cut off the motive fluid entirely from the passage 19, in the valve piece, the movement of the latter will be continued in the same direction until it reaches the position shown in Fig. 6. Now, if the ducts, 22, should become wholly or partially stopped, due to their use as heretofore explained, the valve piece may be turned in the reverse direction until it reaches the position shown in Fig. 5, when the ducts 22 are brought into register with small ports 25 in the valve casing leading to the atmosphere. The throttle valve 36 of the tool may then be closed to cut off the passage of the motive fluid to the tool, and after filling the conduit and the tool between the valve 8 and the valve 36, there will be no escape therefor except through the ducts 22 and ports 25, and these ducts may then be thoroughly cleaned, since the motive fluid is passing therethrough in a direction the reverse of its normal passage, when the ducts are in use for the purpose heretofore explained.

In order to aid the operator in stopping the valve piece in any one of the respective positions disclosed in Figs. 2 to 6 inclusive, it is preferred to equip the handle of the screen valve with a pointer, 26, (see Fig. 7) while the valve casing is provided with marks, 27, 28, and 29, respectively, and stops, 30 and 31. When the pointer is in the position shown by full lines in Fig. 7 or pointing toward the mark 27, the valve piece will be in the position shown in Fig. 2. Now, if it is desired to turn it to the position shown in Fig. 3, the handle, 18, of the valve piece will be turned toward the left, or in the direction indicated by the arrow, until the pointer reaches the mark 28, being one of the positions indicated by dotted lines. Then, if it is desired to move the valve piece to the position shown in Fig. 4 for the purpose of introducing the motive fluid under pressure to the rear of the screen for the purpose of removing the debris clinging to the latter, the handle will be turned in the same direction to bring the pointer to a position in line with the mark 29, being another of the dotted line positions shown in Fig. 7. And, finally, if it is desired to turn the valve piece to a position to cut off the motive fluid entirely from the opening, 19, the handle will be turned to bring the pointer into engagement with the positive stop 30. From this it will be understood that in order to open the valve piece for the passage of motive fluid to the tool, the handle, 18, may be moved in a direction the reverse of the arrow in Fig. 7 until the pointer, 26, again reaches the full line posi-

tion. Again. Should it be desired to clean out the ducts 22, the reverse movement of the handle could be continued until the pointer, 26, engages the positive stop 31 of the valve casing, when the valve piece will be in the position shown in Fig. 5.

From the foregoing description, the use and operation of my improvement will be readily understood, and need not be further described in detail. It should be understood, however, that my improvement may be employed in connection with the straining or screening of any fluid whatever, whether in liquid or gaseous form, and the screen may be cleansed of obstructions in any case by passing the fluid therethrough in the reverse direction from that which it takes when the accumulation of debris has resulted. It will also be understood that the use of my improved valve is general in character, and may be employed in connection with all classes of tools or apparatus where the screening of fluids may become necessary or desirable.

In order to clean the screen or mesh dia-phragm without the employment of the ducts 22 or the port 24, the valve piece 10 may be given a half rotation whereby the screen 20 will be located adjacent the exit extremity of the valve casing whereby the fluid in passing through the opening 19 of the valve piece will act upon the screen in a direction the reverse of that which it traveled during the clogging of the screen. In this event the dirt will be removed from the screen and carried to the inlet pipe 6 which is provided with an outlet port controlled by a valve 32. This valve is normally closed, but when it is desired to clean the screen in the manner just explained it would be opened to allow the dirt to pass through it to the atmosphere in a direct line from the conduit 7, the dirt passing transversely through the inlet 6 and thus avoiding its entrance to the machine. It is preferable to make the outlet port controlled by the valve 32 somewhat larger than the opening through the conduit on the opposite side of the inlet 6 to facilitate perfect freedom in the escape of the dirt which has been removed from the screen. In cleaning the screen in this manner an opportunity is also given for removing any debris which may have accumulated in the conduit between the valve 8 and the inlet 6.

When employing the valve 32 for the escape of the dirt whereby the valve piece 10 is given a one-half rotation, the stops 30 and 31 would not be employed since it would be necessary to give the valve piece a greater degree of movement than is permitted by the said stops. It will thus be understood that I am in no way limited to the details of construction herein described and illustrated in the drawing, as I am

aware that many modifications may be employed without departing from the spirit of the invention as set forth in the appended claims.

5 Having thus described my invention, what I claim is:

1. The combination with means containing a passage for fluid, of a movable valve piece located in said passage and provided

10 with an opening adapted to register with said passage, the valve piece having a mesh diaphragm extending across its said opening and being provided with a duct leading from its outer surface to said opening, its

15 inner extremity communicating with the opening on the outlet side of the diaphragm, the wall of the fluid passage having a port, the outer extremity of said duct being closed by the wall of the passage when the

20 valve piece is in one of the positions when its opening is in communication with the fluid passage on both sides of the valve piece, the valve piece being movable to bring the outer extremity of said duct into communication with said port, while the valve piece opening is still in communication with the fluid passage for the purpose set forth.

2. In a strainer valve for fluid pipes, a valve seat, a valve piece having a passage therethrough, a mesh diaphragm mounted across said passage, said valve piece having a duct therethrough adapted, when the valve piece is in the proper position, to open communication between the front of the

30 valve and the interior of the valve piece upon the normally rear side of the diaphragm, said valve seat having an opening therethrough in a position to open communication between the atmosphere and the 35 normally forward side of the diaphragm when the valve piece is in the said position, said valve seat having a port therethrough adapted when the valve piece is in another position, to register with said duct, said diaphragm being then in substantially the normal position.

3. In combination a fluid pipe, a valve seat, a valve piece rotatable therein, said valve piece having a passage therethrough adapted to be brought into alinement with the bore of said pipe, a mesh diaphragm mounted across said passage, and set in from the side of the valve piece, said valve seat having a port therethrough leading to

50 the atmosphere, said valve being movable to a position to open communication between the bore of the fluid pipe on the inlet side of the valve piece, and the port in the valve seat diagonally across the forward surface 55 of said diaphragm.

4. In combination a fluid pipe, a valve seat, a valve piece rotatable therein, said valve piece having a passage therethrough adapted to be brought into alinement with

60 the bore of said pipe, a mesh diaphragm

mounted across and set in from the forward end of said passage, said valve seat having a port therethrough leading to the atmosphere, said valve being movable to a position to open communication between the bore of the fluid pipe on the inlet side of the valve piece, and the port in the valve seat diagonally across the forward surface 70 of said diaphragm.

5. In combination a fluid pipe, a strainer valve therein comprising a valve seat, a rotatable valve piece to fit said seat, said valve piece having a passage therethrough for registering with the bore of the pipe on either side, a mesh diaphragm mounted 80 across said passage, said valve seat having a port extending therethrough, said valve piece having a duct therethrough so located that when the valve piece is rotated to the proper position, communication will be set 85 up between the bore of the pipe on the inlet side of the valve and the port in the valve seat by way of the duct and passage, the normally forward side of the diaphragm then facing the port, the arc between the 90 outer end of the duct and the middle of the inlet end of the passage being subtended at the center of the valve piece by an angle less than 90 degrees, whereby the above recited communication is made by turning the valve 95 through less than $\frac{1}{4}$ of a revolution from its totally closed toward its open position, or vice versa.

6. In a strainer valve for fluid pipes, a valve seat, a rotatable valve piece to fit said seat, said valve piece having a passage therethrough, a mesh diaphragm mounted across said passage, said valve seat having a port extending therethrough, said valve piece having a duct therethrough so located that 100 when the valve piece is rotated to the proper position, communication will be set up between the bore of the pipe on the inlet side of the valve and the port in the valve seat by way of the duct and passage, the normally forward side of the diaphragm then 105 facing the port, the inlet end of the duct being located near the diaphragm in that wall of the valve piece which is forward when the valve is closed, the walls of the 110 valve seat being arranged to cover the duct when the valve is in the fully closed or the fully open position whereby the communication above recited occurs at a position of the valve piece intermediate the open and 115 closed positions.

7. In a fluid pipe, a strainer valve comprising a valve seat having an inlet and exit, a rotatable valve piece to fit said seat, said valve piece having a passage therethrough, a mesh diaphragm mounted across 125 said passage, said valve seat having a port extending therethrough, said valve piece having a duct therethrough, said valve piece being movable, to a position to open com- 130

munication from said pipe through said duct and screen, to said port, and directly from said pipe against said screen to said port, the diaphragm being large enough to 5 span the arc between the port and the inlet of the valve and the inlet end of the duct being close to the diaphragm in that wall of the valve piece which is forward when the valve is closed, whereby each of said communications will be set up during the movement of the valve piece from open to closed position, or vice versa.

8. In a fluid pipe, a strainer valve comprising a valve seat, a rotatable valve piece 15 to fit said seat, said valve piece having a passage therethrough, a mesh diaphragm mounted across said passage, said valve seat having a port extending therethrough, said valve piece having a duct therethrough, said valve piece being movable to a position to 20 open communication from said pipe through said duct and diaphragm to said port and

directly from said pipe against said diaphragm to said port.

9. In a fluid pipe, a strainer valve comprising a valve seat having an inlet and an exit, 25 a rotatable valve piece to fit said seat, said valve piece having a passage therethrough, a mesh diaphragm mounted across said passage, said valve seat having a port extending 30 therethrough, said valve piece having a duct therethrough extending from the inside of the passage to a point in that wall of the valve piece which is forward when the valve is closed, the distance between said point and 35 the inlet end of the passage being less than the diameter of the inlet of the valve seat.

In testimony whereof I affix my signature in presence of two witnesses.
